UNITED STATES PATENT OFFICE.

WILLIAM FISHER, OF WAYNESBURG, PENNSYLVANIA.

HEATING-FURNACE.

952,426.

Specification of Letters Patent. Patented Mar. 15, 1910.

Application filed June 5, 1909. Serial No. 500,420.

To all whom it may concern:

Be it known that I, WILLIAM FISHER, a citizen of the United States, residing at Waynesburg, in the county of Greene and State of Pennsylvania, have invented a new and useful Heating-Furnace, of which the following is a specification.

This invention relates more particularly to that class of heating furnaces wherein natural or artificial gas is employed for fuel.

The object of the present invention is to provide a furnace which is extremely simple in construction, strong, and durable, and comparatively inexpensive to manufacture; and furthermore, one that may be readily taken apart, and set up into proper position.

Another object of the invention is to provide a furnace structure in which a large radiating surface is had, and in which the products of combustion have a tortuous passage so that all the heat given off by said products is utilized, thus effecting a saving in the cost of maintenance.

With the foregoing objects in view, the invention consists in a novel construction and arrangement of parts to be hereinafter described and claimed, reference being had to the drawings hereto annexed in which—

Figure 1 is a vertical sectional view of the furnace. Fig. 2 is a horizontal section on the line 2—2 of Fig. 1. Fig. 3 is a horizontal section on the line 3—3 of Fig. 1.

Referring to the drawings, there is shown at 5 a base ring which supports the casing 35 of the furnace. The walls of said casing are double to prevent loss of heat, and said casing comprises inner and outer cylindrical shells 6 and 7, respectively, each of which is preferably made in two sections so that 40 the casing may be knocked down for convenience in shipment. The sections are connected by slipping the lower end of the upper section over the upper end of the lower section, there being a bead 9 on the lower 45 section adjacent to the upper end thereof which supports the lower edge of the upper section. Any other suitable separable connection between the sections may be provided. The top of the casing is provided 50 with a hood 10 which is also removable, and is provided with hot air outlets 11 to which the distributing pipes are connected.

Within the casing herein described is mounted a combustion chamber which is 55 formed by concentrically arranged drums 12

and 13, the space between said drums forming the combustion chamber. Near their lower ends the drums are tapered as indicated at 14 and 15. The drum 12 terminates in its tapered portion 14, and the drum 13 has a reduced portion 15^a extending below the same. The lower end of the reduced portion 15^a of the drum 13 is open, and the tapered lower end 14 of the drum 12 is closed by the burner to be presently described.

At the lower end of the portion 15^a of the drum 13 is located an annular smoke box 17 having adjacent to its inner periphery an upstanding flange 18 over which the said portion 15^a is slipped whereby the drum is held in place on the smoke box. The upper end of the space between the drums 12 and 13 is closed by an annular cap 19 having adjacent to its inner and outer peripheries 75 depending annular flanges 20 and 21 respectively. The flange 20 is slipped over the upper end of the drum 12, and the flange 21 slips over the upper end of the drum 13. The cap therefore serves to close the space 80 between the drums at the upper end thereof.

Extending between the cap 19 and the smoke box 17, are flues 22. These flues enter the top of the combustion chamber through the cap 19, and serve to carry the 85 products of combustion from the said combustion chamber into the smoke-box 17, they entering the bottom of the latter. From the top of the smoke-box leads a flue or pipe 23 through which the fumes escape. The 90 flues 22 are made in separable sections in order that the various parts herein described may be assembled. The joint between the flue sections may be an ordinary telescopic joint.

The burner is a cylindrical casing 24 mounted within the reduced portion 15^a of the drum 13, said casing extending concentric thereto. The casing is provided with burner openings 25, and its lower end is 100 conical as indicated at 26. The cone-shaped lower end of the burner casing is surrounded by the smoke-box 17, there being sufficient space between said parts to permit air to flow past the burner openings 25 into the 105 combustion chamber. Air enters the casing of the furnace through an inlet 28 at the bottom thereof.

On the inside of the burner casing 24 is located a cylinder 14^a extending concen- 110

trically to the casing and being closed and cone-shaped at its lower end as indicated at 16, said cone-shaped end being concentric to the cone-shaped portion 26 of the burner 5 casing. The space between the burner casing and the cylinder 14^a is closed at its upper end by a flange 16^a which engages the lower edge of the drum 12, and this flange has an upstanding portion 16^b fitting within 10 said drum whereby the burner is supported in place by the frictional engagement of the portion 16^b with the drum. By the cylinders 14^a and 24 herein described, an annular burner is had, the lower end of which is open 15 and is entered by a fuel supply pipe 27. The cone 16 spreads the fuel and guides it to the burner openings 25. The cylinder 14^a also serves to close the lower end of the drum 12.

20 A short distance above the burner, a flue 29 extends across the combustion chamber, said flue opening at one end into the casing, and at the other end into the inner drum 12.

The casing is provided with a door 30, 25 and in the portion 15^a of the drum 13 is an opening 31 in order that access to the burner, for the purpose of lighting the same may be had, said opening being provided with a door 32.

30 The drum 12 is connected with the drum 13 by brackets 33. The burner is supported by the drum 12, and the drum 13 is supported on the smoke drum 17. A separable connection between these parts is had, in 35 view of which the furnace can be shipped in knock-down form. The parts are so arranged and constructed that they can be easily set up or assembled. The casing of the furnace also consists of separable sections as already described.

40 The smoke-box 17 is supported on legs 34 secured to a band 35 clamped around said smoke-box. These legs serve to support the smoke-box and the parts carried thereby a 45 suitable distance above the floor.

The furnace operates as follows: Air enters the inlet 28 and passes out of the furnace through the outlets 11. A portion of the air passes into the combustion chamber. 50 The air also passes through the flue 29 into the drum 12. The products of combustion pass upwardly into the space between the drums 12 and 13, and thence downwardly through the flues 22 into the smoke-box 17, 55 and out of the same through the pipe 23. By providing the herein described annular combustion chamber, a large heating surface is presented to the air in passing through the casing, and the same is rapidly heated. 60 The air also circulates around the flues 22 and the latter form an additional heat-radiating surface.

What is claimed is:

1. A heating furnace comprising a casing 65 having an air inlet at the bottom, and an air

outlet at the top, concentric drums in the casing, said drums being spaced from each other and from the casing, the space between the drums forming an annular combustion chamber, and said space being closed at its 70 upper end, and open at its lower end, the lower end of the outer drum being reduced in diameter and extending below the inner drum, and the inner drum being open at its upper end, a flue extending across the combustion chamber, said flue opening at one end into the casing, and at the other end into the inner drum, an annular burner comprising inner and outer concentric cylinders 75 cone shaped at their lower ends, the outer cylinder having burner openings, and the inner cylinder being closed at its lower end, and in communication with, and closing the lower end of the inner one of the aforesaid drums, an annular smoke-box on which the 80 lower end of the outer drum is supported, said smoke-box being spaced from and surrounding the lower end of the burner below the burner openings, flues connecting the upper end of the combustion chamber with 85 the smoke-box, an outlet pipe from the smoke-box, and a fuel inlet to the burner at the lower end of the outer cylinder.

2. In a heating furnace, a base, a casing 90 removably supported thereon, an annular smoke-box, an outlet pipe from the smoke box, supporting means for the smoke box, concentric drums spaced from each other and from the casing, and removably supported on the smoke-box, the space between 95 the drums forming a combustion chamber, a cap removably mounted upon the upper ends of the drums, and closing the space therebetween, flues extending between the cap and the smoke-box, said flues comprising 100 separable sections connected respectively to said cap and the smoke-box, and a burner removably supported by the inner one of the aforesaid drums at its lower end.

3. A heating furnace comprising the cas- 110 ing having an air inlet at the bottom, and an air outlet at the top, concentric drums in the casing, said drums being spaced from each other and from the casing, the space be- 115 tween the drums forming an annular com- bustion chamber, and said space being in- closed at its upper end, and open at its lower end, the inner drum being open at its upper end, a flue extending across the combustion chamber, said flue opening at one end into 120 the casing, and at the other end into the inner drum, an annular burner comprising inner and outer concentric cylinders, the outer cylinder having burner openings, and the inner cylinder being closed at its lower end, and in communication with and clos- 125 ing the inner one of the aforesaid drums, an annular smoke-box on which the lower end of the outer drum is supported, said smoke- 130 box being spaced from and surrounding the

lower end of the burner below the burner openings, flues connecting the upper end of the combustion chamber with the smoke-box, an outlet pipe from the smoke-box, and a 5 fuel inlet to the burner at the lower end of the outer cylinder.

In testimony that I claim the foregoing

as my own, I have hereto affixed my signature in the presence of two witnesses.

WILLIAM FISHER.
